US0D1029033S

(12) **United States Design Patent** (10) Patent No.: US D1,029,033 S
Carli et al. (45) Date of Patent: ** May 28, 2024

- (54) **DISPLAY SCREEN OR PORTION THEREOF WITH GRAPHICAL USER INTERFACE**

(71) Applicant: **IGT**, Las Vegas, NV (US)

(72) Inventors: **Matteo Carli**, Reno, NV (US); **Gary Chien**, Reno, NV (US); **Fazley Chowdhury**, Reno, NV (US); **Emilia Ciardi**, Lavena Ponte Tresa (IT); **Jorgen Johnson**, Las Vegas, NV (US); **Darren Maya**, Reno, NV (US); **Ronald Papson**, Reno, NV (US); **Allan Snippen**, Reno, NV (US); **Matthew Tarbox**, Reno, NV (US); **Tamer Uz**, Reno, NV (US)

(73) Assignee: **IGT**, Las Vegas, NV (US)

(**) Term: **15 Years**

(21) Appl. No.: **29/916,611**

(22) Filed: **Nov. 14, 2023**

CLAIM

The ornamental design for a display screen or portion thereof with graphical user interface, as shown and described herein.

DESCRIPTION

The file of this patent contains at least one drawing/photograph executed in color. Copies of this patent or patent application with color drawing(s)/photograph(s) will be provided by the Office upon request and payment of the necessary fee.

FIG. 1 is a front view of a display screen or portion thereof with graphical user interface showing a first embodiment of our new design; and,

FIG. 2 is a front view of a display screen or portion thereof with graphical user interface showing a second embodiment of our new design.

The dashed broken line perimeter in the drawings illustrates a display screen or portion thereof and forms no part of the claimed design.

1 Claim, 2 Drawing Sheets
